UNITED STATES PATENT OFFICE.

CARL SCHWARZ, OF ROSTOCK, GERMANY, AND HUGO SCHWARZ, OF CHICAGO, ILLINOIS.

BOAT WATER-CLOSET.

Application filed January 9, 1928, Serial No. 245,375, and in Germany April 20, 1927.

This invention relates to improvements in water closets particularly adapted, though not necessarily limited in its use, in boats, and one of the objects of the invention is to provide an improved water closet of this character from which the excrements may be readily removed and which will operate efficiently either with or without the use of water to flush the same.

A further object is to provide an improved water closet of this character which will operate efficiently either above or below the water level without danger of flooding the closet.

A further object is to provide an improved water closet of this character which will be of a simple and durable construction, effective and efficient in operation and which may be permanently or removably secured in position.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

Figure 1 is a side elevation with the cover closed.

Figure 2 is a front elevation, partly in section, showing the cover open.

Figure 3 is a vertical, sectional view taken on line 3—3, Figure 2.

Figure 4 is a vertical, sectional view taken on line 4—4, Figure 1.

Figure 5 is an enlarged detail sectional view of a portion of the cylinder and plunger with the locking means for locking the plunger members together and for releasing them.

Referring more particularly to the drawings the numeral 10 designates generally the bowl of a closet which is mounted upon a tubular support 11. The support is provided with a base flange 12 by means of which the closet may be secured in position. The flange 12 is adapted to enter guideways 13 that are secured to a base or floor 14 by means of suitable fastening devices 15. The guideways serve as a means whereby the closet may be permanently secured in position or adapts the same to be readily removed by sliding the flange out of the guideways 13.

Arranged within the tubular supporting base 11 of the closet is a cylinder 16 which

may be formed of any suitable material preferably of some non-corrosive and durable material which may be separate from the base 11 or may be constituted by a portion of the support. This cylinder 16 is open at the top, and the bottom 17 thereof inclines downwardly from the periphery of the cylinder towards the diametric center to provide an opening 18 located preferably at the diametric center of the cylinder 16. Leading from the opening 18 is a discharge outlet 19 preferably in the form of a pipe which may be of a sectional construction, a portion thereof projecting through the wall of the upright 10 and to which pipe 19 may be connected a discharge pipe 20 of any suitable character either flexible or non-flexible and through which discharge pipe 20 the excrements are delivered when the closet is operated.

A valve 21, preferably in the form of a flap valve, is provided for closing the opening 18 and this valve 21 is provided with a counterbalancing weight 22. The weight 22 tends normally to hold the valve 21 closed and the valve 21 operates from the underside of the bottom 17 so that in the event the closet is arranged below the water level, any water entering the pipe 19 from the outside will assist in holding the valve 21 closed.

Under normal conditions the weight 22 is sufficiently heavy to hold the valve 21 closed.

A catch basin 23 may be provided around the valve 21 for any water which may pass through the bearing of the valve 21 and this catch basin may be provided with a removable closure 24, which latter may be removed when desired to permit the removal of water and foreign matter from the catch basin.

The cylinder 16 may be of any desired size and height and arranged to reciprocate therein is a plunger which consists of a body member 25 and a cover member 26, the two being pivotally connected as at 27. The body member 25 is preferably of an annular construction or is shaped to provide an opening 28 therethrough which is of considerable area and the member 26 is provided with a flange 29 adapted to engage and rest upon the member 25. If desired a suitable packing or gasket 30 may be provided in the member 25 to be engaged by the flange 29 and thereby form a liquid tight joint.

Carried by the member 25 is a catch 31 which is pivotally connected thereto by one end as at 32 and a shoulder 33 is formed on

the catch; the shoulder being adapted to engage over the flange 29 to lock the members 25 and 26 together.

Within the wall of the cylinder (shown in Figure 5 as being in the tubular support 11 and in Figure 3 as being in the wall of the cylinder 16) is an opening 34 having an inclined bottom 35 so that when the plunger is elevated the upper end of the catch 31 will be directed into the opening 33, the catch 31 being top heavy so as to cause the same to fall over its pivot 32 as it reaches the opening 34.

When the plunger 25 is lowered the catch 31 will be moved by the upright wall of the cylinder (or the support 11) about its pivot to position the shoulder 33 over the flange 29 and thereby lock the members 25 and 26 together.

If desired suitable packing 36 may be provided in the member 25 to form a liquid tight joint.

The member 26 may, if desired, be hollow. The closet is provided with the usual seat 37 to which a cover 38 is pivotally connected as at 39. A link 40 is pivotally connected at one end as at 41 to the inside of the cover 38 and is pivotally connected at its other end 42 to the member 26 of the plunger and the member 26 is adapted to be moved with respect to the member 25 and about its pivot 27 by means of the lowering movement of the cover 38.

When the cover 38 is raised the parts will be in the position shown in Figure 3, that is the catch 31 will be in a position to release the member 26 and the member 26 will be elevated by the link 40 and at the same time the member 25 will be at the limit of its upward movement in the cylinder. The valve 21 will also be closed either by the weight 22 or by the pressure of liquid under the valve forcing the valve against its seat.

To operate the closet the cover 38 is lowered, the link 40 will then swing the member 26 about its pivot 27 until the flange 29 engages and rests upon the member 25. This will occur before the cover is completely closed. A further closing movement of the cover 38 will cause the plunger constituted by the members 25 and 26 to be forced downwardly in the cylinder 16. As the plunger lowers the member 25 traveling downwardly in the cylinder will cause the catch 31 to swing about its pivot 32 to lock the members 25 and 26 together so that they will both continue in a downward movement and the member 26 will be held against opening movement under force of any pressure exerted against the lower side of the member 26 from within the cylinder 16. The lowering of the plunger will force the excrements from the cylinder 16 by swinging the valve 18 about its pivot so that the excrements may be discharged into the delivery pipe 19. As soon as the cylinder 16 is empty the valve 21 will close and

as the cover 38 is raised the plunger will also raise until the end of the catch 31 reaches the opening 34, at which time the catch will enter the opening 34 to unlock the member 26 with respect to the member 25, thereby permitting the cover 38 to be moved to a full open position and at the same time the member 26 will be raised to the position shown in Figure 3.

Obviously the plunger consisting of the members 25 and 26 locked together may be reciprocated in the cylinder 16 by a proper manipulation of the cover 38 and before the catch 31 enters the opening 34 to unlock the member 26 from the member 25.

It will be manifest that it will not be necessary to install running water in the closet, but if desired and on account of cleanliness water may be employed.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A toilet embodying a bowl, a valved outlet therefor, a plunger, there being an opening through the plunger, a closure for the opening, means for reciprocating the plunger, and interengaging means on the plunger and said closure and operating automatically at predetermined times in the cycle of operation of the plunger for locking the said closure with respect to the plunger for movement with the plunger and to close the said opening therein and for releasing the closure to permit the latter to swing with respect to said plunger to uncover the opening in the plunger.

2. A toilet embodying a bowl, a valved outlet therefor, a plunger, there being an opening through the plunger, a closure for the opening, a lid for the bowl, means responsive to the movements of said lid for reciprocating the plunger, and means operating automatically at predetermined times in the cycle of operation of the plunger for locking the said closure with respect to the plunger for movement with the plunger and to close the said opening therein and for releasing the closure to permit the latter to swing with respect to said plunger to uncover the opening in the plunger.

3. A toilet embodying a cylindrical portion having a discharge outlet, a valve for controlling said outlet, a plunger reciprocable in said cylindrical portion for forcing the contents of the toilet past said valve and into the discharge outlet, said plunger embodying two members connected together for bodily movement together and for relative movement one with respect to the other, one of said members having an opening there-

through and the other constituting a closure for such opening, a latch connected with one of the members for engagement with the other member for automatically locking the members for movement together and for releasing them, and means for reciprocating the plunger.

4. A toilet embodying a cylindrical portion having a discharge outlet, a valve for controlling said outlet, a plunger reciprocable in said cylindrical portion for forcing the contents of the toilet past said valve and into the discharge outlet, said plunger embodying two members connected together for bodily movement together and for relative movement one with respect to the other, one of said members having an opening therethrough and the other constituting a closure for such opening, means independent of the plunger reciprocating means for automatically locking the members for movement together and for releasing them, and means for reciprocating the plunger, when the members are locked together and for imparting a relative movement to the members when they are unlocked whereby the said opening will be uncovered.

5. A toilet embodying a cylindrical portion having a discharge outlet, a valve for controlling said outlet, a plunger reciprocable in said cylindrical portion for forcing the contents of the toilet past said valve and into the discharge outlet, said plunger embodying two members hingedly connected together for bodily movement together and for relative movement one with respect to the other, one of said members having an opening therethrough and the other constituting a closure for such opening, means carried by one of the members and engaging the other member for automatically locking the members for movement together and for releasing them, a closure for the said cylindrical portion, and an operative connection between the last said closure and one of the plunger members whereby the operation of the second recited closure will actuate the plunger and also impart a relative movement to the plunger members one with respect to the other to uncover the opening through one of the plunger members.

6. A toilet of the character described embodying an open cylindrical portion having a discharge outlet, means tending normally to close said outlet, a piston reciprocable in said cylindrical portion for forcing excrements from the cylinder past the said means and through the said outlet, said piston embodying a member having an opening therethrough, a second member hingedly connected with the first said member and operable to close said opening, means for reciprocating the piston, means separate from the piston reciprocating means for automatically locking said hinged member in a closed po-

sition, and means for other than the piston reciprocating means rendering the locking means active and inactive.

7. A toilet of the character described embodying an open cylindrical portion having a discharge outlet, means tending normally to close said outlet, a piston reciprocable in said cylindrical portion for forcing excrements from the cylinder past the said means and through the said outlet, said piston embodying a member having an opening therethrough, a second member hingedly connected with the first said member and operable to close said opening, means carried by one of said members and engageable with the other member for automatically locking said hinged member in a closed position, means other than the piston reciprocating means for rendering the locking means active and inactive, and means for reciprocating the piston, the last recited means also operating to swing the said hinged member about its pivot with respect to the other said member when said locking means is inactive.

8. A toilet of the character described embodying a cylindrical portion having a discharge outlet, a plunger reciprocable in said portion, said plunger embodying a member having an opening therethrough for the passage of excrements, a second member hinged to the first said member and operating as a closure for said opening, means pivotally connected with one of said members and adapted to engage the other member for locking said hinged member in a position to close said opening, whereby the plunger will force the excrements through said discharge outlet, and means for reciprocating the plunger.

9. A toilet of the character described embodying a cylindrical portion having a discharge outlet, a plunger reciprocable in said portion, said plunger embodying a member having an opening therethrough for the passage of excrements, a second member hinged to the first said member and operating as a closure for said opening, a shiftable catch carried by one of said members to engage the other member for locking said hinged member in a position to close said opening, whereby the plunger will force the excrements through said discharge outlet, means for reciprocating the plunger, and means arranged adjacent the path of movement of said catch with its supporting member for automatically rendering said locking means active and inactive.

10. A toilet of the character described embodying a cylindrical portion having a discharge outlet, a plunger reciprocable in said portion, said plunger embodying a member having an opening therethrough for the passage of excrements, a second member hinged to the first said member and operating as a closure for said opening, means for locking said hinged member in a position to close said

opening whereby the plunger will force the excrements through said discharge outlet, means for reciprocating the plunger, the said locking means embodying a catch pivotally connected with one of said members, and an opening in the wall of the cylindrical portion and into which opening the catch will enter when the plunger is in a predetermined position in the cylindrical portion and thereby 10 unlock the said hinged member.

11. A toilet of the character described embodying a cylindrical portion having a discharge outlet, means tending normally to close said outlet, a plunger reciprocable in the cylinder, said plunger embodying a member having an opening therethrough through which excrements may pass, a second member hingedly connected to the first said member for closing the last said opening, means 15 for maintaining the hinged member in a position to close said opening whereby the plunger will force the excrements past the first said means and through said discharge outlet, a cover for the toilet, and an operative connection 20 between the said cover and the plunger whereby the reciprocation of the plunger will be responsive to the operation of said cover.

12. A toilet of the character described embodying a cylindrical portion having a discharge outlet, means tending normally to close said outlet, a plunger reciprocable in the cylinder, said plunger embodying a member having an opening therethrough through which excrements may pass, a second member 25 hingedly connected to the first said member for closing the last said opening, means for maintaining the hinged member in a position to close said opening whereby the plunger will force the excrements past the 30 first said means and through said discharge outlet, a cover for the toilet, and a connection between the cover and the said hinged member whereby the plunger will be reciprocated by the operation of the cover, said connection 35 also operating to swing the hinged member with respect to the other member of the piston to uncover the opening through the latter when the hinged member is released.

13. A toilet of the character described embodying a cylinder having a discharge outlet, a plunger reciprocable in the cylinder for forcing excrements therefrom, there being an opening permitting excrements to pass through the plunger, means for reciprocating 50 the plunger, means responsive in its operation to the actuation of the last said means for closing the last said opening whereby the movement of the plunger will force the excrements out of the said discharge outlet, and 55 means other than the plunger reciprocating means for maintaining the second recited

means in a position to close said opening in the plunger.

14. A toilet of the character described embodying a cylinder having a discharge outlet, a plunger reciprocable in the cylinder for forcing excrements therefrom, there being an opening permitting excrements to pass through the plunger, means for reciprocating the plunger, means responsive in its operation to the actuation of the last said means for closing the last said opening whereby the movement of the plunger will force the excrements out of the said discharge outlet, means other than the plunger reciprocating means 65 for locking the second recited means in a position to close said opening in the plunger, and means also separate from the plunger reciprocating means for automatically rendering said locking means active and inactive. 70

15. A toilet of the character described embodying a cylinder having a discharge outlet, a plunger reciprocable in the cylinder for forcing excrements therefrom, said plunger embodying a member having an opening 75 therein for permitting excrements to pass through the plunger and a member hinged to the first said member and operable to close said opening, means for reciprocating the plunger, a catch pivoted to one of the members for locking the hinged member in a closing position, said catch being rendered active by the wall of the cylinder when the piston is moved, an opening in the cylinder wall into which the catch will move at a predetermined 80 time in the cycle of operation of the plunger for rendering the catch inactive, and means for reciprocating the plunger.

16. A toilet of the character described embodying a cylinder having a discharge outlet, 100 a plunger reciprocable in the cylinder for forcing excrements therefrom, said plunger embodying a member having an opening therein for permitting excrements to pass through the plunger and a member hinged to the first said member and operable to close 105 said opening, means for reciprocating the plunger, a catch pivoted to one of the members for locking the hinged member in a closing position, said catch being rendered active 110 by the wall of the cylinder when the piston is moved, an opening in the cylinder wall into which the catch will move at a predetermined time in the cycle of operation of the plunger for rendering the catch inactive, a cover for 115 the toilet, and a link connection between said cover and the said hinged member of the plunger.

In testimony whereof we have signed our names to this specification.

CARL SCHWARZ.
HUGO SCHWARZ,
